UNITED STATES PATENT OFFICE.

HENRY E. KIRSTEIN, OF ROCHESTER, NEW YORK.

DESIGN FOR AN EYEGLASS OR PINCE-NEZ SPRING.

SPECIFICATION forming part of Design No. 35,653, dated February 4, 1902.

Application filed May 22, 1901. Serial No. 61,460. Term of patent 14 years.

To all whom it may concern:

Be it known that I, HENRY E. KIRSTEIN, a citizen of the United States, residing at Rochester, in the county of Monroe and State of New York, have invented and produced a new and original Design for an Eyeglass or Pince-Nez Spring, of which the following is a specification, reference being had to the accompanying drawings, forming a part thereof.

My design relates to springs for eyeglasses or pince-nez; and it consists of the spring formed as shown in the accompanying drawings, in which—

Figure 1 is a perspective view of a spring of my design; Fig. 2, a sectional view, and Fig. 3 a plan view, of the same.

The feature of the design is the shape or configuration of the spring, embodying the

bowed or curved body portion 1, having the short bends 2 at the ends thereof, and beneath 20 these the short ends 3, extending at a slight angle relatively to the plane of the body of the spring, as shown in Fig. 2, and also extending slightly tangentially of the curve of the body, as shown in Fig. 3. 25

Springs constructed in accordance with my design are of graceful form and present a pleasing appearance.

I claim—

The design for an eyeglass or pince-nez 30 spring, substantially as herein shown and described.

HENRY E. KIRSTEIN.
